SOLE SANDING MACHINE

John A. Harrington and Kitchener B. Tassell, Grand Rapids, and Alden V. Hardick, Muskegon, Mich., assignors to Wolverine World Wide, Inc., a corporation of Michigan

Filed Jan. 28, 1965, Ser. No. 428,679
11 Claims. (Cl. 51—34)

This invention relates to shoe machinery, and more particularly to a machine for abrading the heel area of a molded shoe sole.

Molded shoe soles of polymeric materials such as synthetic rubber presently are preferably made with a three dimensional pattern molded into the sole bottom. Since the heel of the shoe is normally adhesively attached to the bottom of the flat sole, and since the three dimensional pattern prevents effective adhesion, the pattern must be removed in the heel area of the sole bottom, as by abrasion. To do this economically, soles must be abraded in rapid succession. Since the pattern must be removed in all of the heel area, but in no more than this specific area, accuracy of abrasion is very important. Yet, the high friction characteristics, especially of rubber soles, renders them difficult to automatically manipulate for abrading. They resist sliding with respect to each other and with respect to the support surface.

Prior to this invention, therefore, it has largely been deemed necessary to manually feed and control each sole into an abrading head because of these and other difficulties inherent in the nature of the materials and process.

It is an object of this invention to provide a novel heel area sole abrading apparatus capable of high speed, automatic abrasion of pattern soles, in the heel area and only in the heel area.

Another object of this invention is to provide a unique apparatus capable of rapidly feeding rubber soles from a stack in a sliding action, abrading them automatically in rapid succession, and dependably discharging them.

Another object of this invention is to provide an automatic sole abrading apparatus having complete accuracy to abrade exactly the heel area, no more and no less. The device repeatedly feeds new soles in and abraded soles out, while simultaneously abrading soles, thereby being very efficient. Each sole is slid smoothly and dependably along the machine, even though it is formed of high friction material. The nature of the apparatus assures complete alignment of each sole with the abrading head. The apparatus can accommodate right-foot soles, left-foot soles, large soles or small soles.

These and several other objects of this invention will become apparent upon studying the following specification in conjunction with the drawings in which:

FIG. 1 is a perspective front view of the novel machine;

FIG. 2 is a fragmentary, end elevational view of the machine in FIG. 1;

FIG. 3 is a plan view of the novel apparatus;

FIG. 4 is a sectional view of the apparatus, taken on plane IV—IV of FIG. 3;

FIG. 5 is a view of the apparatus, taken in the direction indicated at V—V in FIG. 4;

FIG. 6 is a fragmentary, enlarged, perspective view of the operative components on the apparatus in one position;

FIG. 7 is a fragmentary, enlarged, perspective view of the apparatus in a second position;

FIG. 8 is a schematic diagram of the pneumatic circuit controlling the apparatus;

FIG. 9 is a plan view of a sole and the feed-in fingers of the machine;

2

FIG. 10 is a front elevational view of the elements in FIG. 9;

FIG. 11 is an enlarged, front, elevational view of a portion of the work platform and a holding hook; and

FIG. 12 is a fragmentary, enlarged, perspective view of a portion of the feed hopper.

Referring now specifically to the drawings, the complete abrading machine assembly 10 includes a support frame sub-assembly 12, a shoe sole hopper sub-assembly 14, a slanted feed and operating table sub-assembly 16, a shoe sole feed and discharge sub-assembly 18, a carriage sub-assembly 19, an abrading head sub-assembly 20, a clamping sub-assembly 22, and a sole receiving discharge chute sub-assembly 24.

Framework

The supporting framework sub-assembly 12 includes components to support the other sub-assemblies in cooperative relationship. It includes, for example, a table-type stand 30 with its plurality of depending legs, and upon which are supported the remaining sub-assemblies along its length.

Platform

Extending a substantial portion of the length of this support is the slanted feed and operating table sub-assembly 16. This includes an upper platform 36 slanted downwardly and rearwardly toward the back of the unit, at an angle of approximately 45°. The platform is purposely slanted to cause the elongated soles to maintain constant positioning with respect to the grinder. This is because the sole tends to slide to the bottom of the table no matter what its position along the table. It abuts an elongated stop flange or ridge 50 (FIGS. 2, 4 and 6) along the bottom rear table edge. As will be noted hereinafter, all of the other components are tilted to cooperate with the tilted table. The table must tilt at a substantial angle to assure the sliding action, and yet must allow the sole to rest on it. Hence, the preferred angle is about 45° as indicated, but can be slightly more or less, provided these conditions are met. Slanted soles pushed along the table have the heel area edge in contact constantly with flange surface 50.

This platform is mounted on a pair of rigid standards 38 and 39 (FIG. 1) on opposite ends. The standards each have a base affixed to a pair of pillars 40 and 42. The pillars rest on and are affixed to support 30. Platform 36 includes a longitudinal slot 46 (FIG. 2) extending along its length and positioned generally in its center. This slot allows sole-pushing fingers to move therein as described hereinafter.

Feed hopper

On one end of the slanted operating table or platform (the left end as the structure is viewed in FIG. 1) is a feed hopper sub-assembly 14. It feeds individual soles to the working platform. This sub-assembly includes a pair of upstanding plates 54 and 56 which generally converge downwardly and backwardly into abutment with a back panel 58. These three panels form the receiving hopper for a stack of soles. The heels of the soles abut against panel 58 when placed in the hopper.

The hopper can be varied in width and configuration by clamping mechanisms 55 and 57 (FIG. 5) which enable the panels to be adjusted. This accommodates soles of different size, and right or left foot soles.

The back surface of back panel 58 of the hopper is coated with a lubricious plastic such as nylon or Teflon to assure smooth sliding of the soles down the hopper as soles are removed from the bottom. Also, the back panel is at an obtuse angle with respect to platform 36 to cause only slight line contact between the heel of

each sole and back panel 58. This assures minimum frictional resistance due to minimum contact area. The soles are automatically moved one at a time out of the bottom of the hopper and across platform 36, by being slid through an opening 60 in the bottom of panel 56 (FIG. 5). Since the platform 36 is slanted, if the hopper gets almost empty for refill, a large heavy sole on the bottom may tend to "fall" out of the hopper through opening 60 if there are no soles on top of it to hold it in place. Hence, a spring element 59 (FIGS. 3 and 12) is attached to hopper wall 56 near the upper end of opening 60 to prevent this. This element has its lower end extending over a portion of opening 60, and is biased in this position. It can be deflected temporarily upwardly with forceful shifting of the bottom sole S through opening 60 for egress of the sole.

A plurality of small rollers 62 are rotatably mounted in platform 36 beneath the hopper, and particularly along its upper front end portion. This is to cause smooth discharge of big soles from the base of the hopper, even though several other rubber soles are mounted on top of, and press down on the sole to be removed.

Sole feed means

The bottom sole is shifted out of the hopper by a pair of spaced, projecting, shiftable feed fingers 70 and 72 (FIG. 5). The front finger 70 is L-shaped, or dogleg-shaped. It projects above the upper surface of platform 36 adjacent its front edge. The second finger 72 projects above the surface of platform 36 through slot 46 (FIG. 2).

These two fingers have their lower ends mounted in a pair of like L-shaped brackets 76. The two brackets are essentially identical and appear like the one front bracket 76 shown for finger 70 (FIG. 7). Both of these brackets have their lower ends fixedly attached to a pivotal rod 80 (FIG. 7) extending through a surrounding sleeve 82 transverse to the table, parallel thereto. Rotating of rod 80 causes pivoting of the two brackets to move fingers 70 and 72 from the protruding position (FIGS. 2 and 5) to the depressed position (FIG. 6).

The shape of finger 70 is important since its laterally extending upper end portion engages different length soles in optimum manner. More specifically, as illustrated in FIG. 9, even though the sole may vary in length, and thus, the portion S1 of the sole S will be in a different position with respect to the back hopper panel 58 and guide surface 50, dogleg finger 70 will contact it along the instep area for effective cooperative removal with finger 72.

Each of upwardly projecting fingers 70 and 72 has a beveled forward upper edge, 71 and 73 respectively (FIG. 9), and shown most clearly at 71 on finger 70 (FIG. 10). Also, the total thickness or height of the fingers is greater than the thickness of the sole S so that the beveled edge 71 protrudes above the sole to be shifted. Thus, as the fingers shift the bottom sole S out from under the stack of soles S2, S3, S4, etc, in hopper 14, this beveled edge lifts the overlying sole off the shifted sole to minimize and substantially eliminate frictional drag between the bottom most sole and the others normally resting thereupon. This enables the sole to be readily shifted through opening 60 in the hopper (FIG. 5) for removal on a high speed production basis.

Sole discharge means

A second set of spaced, projecting, sole shifting fingers 86 and 88 (FIG. 2) are spaced from fingers 70 and 72 along the platform toward the discharge end of table 36 (the right end as viewed in FIG. 1). These are sole-discharge fingers which push the abraded sole from the central work zone of the platform and discharge it down chute 24. These fingers, like fingers 70 and 72, are shiftable from a first position projected above the table (FIG. 2) to a second position beneath the surface of the table

(FIG. 6). They are mounted to the outer ends of L-shaped brackets 90 and 92 (FIG. 4) which have their lower ends mounted to a pivotal shaft 96 rotatable in sleeve 98.

5 The two sleeves 82 (FIG. 7) and 98 (FIG. 4) for the two sets of fingers both have their rear ends affixed to an upstanding support plate 100 (FIG. 4). This plate is part of the movable carriage assembly to be described. Each of the pivotal rods 96 and 80 has extending downwardly therefrom a pair of fixed respective ears, e.g. ears 104 and 106 (FIG. 4) for rod 96 and ears 105 for rod 80 (FIG. 5). The lower ends of these ears are pivotally attached as by pins 108 and 110 to the extended end of links 112 and 113 (FIG. 5) connected to rod 114 of the piston in a fluid cylinder 116. The cylinder is also mounted to the carriage by mount 117. Actuation of cylinder 116 in opposite directions causes linkage shifting for pivoting L-shaped brackets for elevating the fingers simultaneously above the table or alternatively, 10 simultaneously depressing them beneath the table surface. As will be explained hereinafter, the unit can thus simultaneously feed an unabraded sole from hopper 14 to the grinder by fingers 70 and 72, and discharge an abraded sole to chute 24 with fingers 86 and 88, while 15 they move to the right across the table (as the structure is viewed in FIG. 1). When depressed, they can move backward beneath the table.

Carriage and abrader

20 The fingers are shifted back and forth across table 36 by carriage sub-assembly 19 (FIG. 4). This carriage sub-assembly includes a pair of sleeve guides 130 and 132 which fit around a pair of fixed guide rods 134 and 136, respectively, aligned with the table. The slide or guide rods 134 and 136 can be protected from the rubber material abraded from the shoe soles by sets of bellows 137 and 139 if desired (FIG. 5).

25 Attached to the sleeves is plate 100 that mounts finger bracket sleeves 96 and 80. Also mounted on this carriage 30 is the motor 140, on the output shaft 142 of which is affixed a cylindrical abrading cylinder 144. The cylinder has a cover guard 146. The housing 146 around the abrading cylinder has a flexible exhaust hose 147 attached thereto and extending to a suitable outlet for the abrasive particles to be vented.

35 This carriage is shifted by a fluid cylinder 160 (FIG. 3) affixed to the support frame. It has its extending shaft 162 (FIG. 4) attached to the underslung bracket 166 of the carriage sub-assembly to push and pull it back and forth across the mechanism. Shifting of the carriage toward the feed hopper moves not only the two sets of fingers as described, but also the abrading wheel and its driving motor. The abrading wheel, therefore, can move back and forth over the central work portion of the table, 40 while the feed fingers 70 and 72 move between the feed hopper and the table center to shift a sole out of the feed hopper to the work area, and the discharge fingers move between the center of the table and the discharge chute to push abraded soles from the work area.

Sole clamping means

45 Mounted to operate adjacent the center of the table, and cooperative with both pairs of fingers and the abrading wheel, is the sole clamping sub-assembly 22. This 50 clamping mechanism is mounted on an upwardly extending, rigid bracket 180 (FIG. 1) and more specifically, on a vertical extension 182 therefrom. Basically, it includes a V-shaped rocker clamp arm 184 (FIG. 4) pivotally mounted adjacent its center apex 186 between a 55 pair of bracket ears 188 depending from support 182. The lower rear end of rocker arm 184 extends over the top of table 36 at its center (FIG. 4). Attached to this lower end is a sole clamping pad 190 which clamps soles against table 36 with the heel area exposed. This clamp 60 can be actuated by shifting its rear end 184' upwardly

with the extended rod 192 of a fluid cylinder 194 mounted in bracket 180. A tension spring 196 returns the clamp to its release position when cylinder 194 retracts.

Retaining hook

Mounted to the front edge of platform 36 adjacent the clamp sub-assembly is a tiny sole retaining hook 200 (FIGS. 7 and 11). This retaining hook is secured to the edge of platform 36 as by a screw 202, so that its upper hooking edge 204 projects above the surface of platform 36. This forms a stop surface for a sole which has been pushed up over the adjacent curved or beveled slanted surface 206, leading up to ledge 204. Thus, a sole aligned on table 36 with its long axis upwardly on the slant, and pushed laterally in the direction indicated by the arrow in FIG. 11 by loading fingers 70 and 72, will ride up lead-on slope 206 and drop down behind ledge 204 as indicated by the phantom sole at S in FIG. 11. This prevents it from sliding back downwardly in rotating fashion to an askew position when loading fingers 70 and 72 retract away from the sole and return to the feed hopper. If it did slide back, the abrasion operation would be entirely inaccurate.

For convenience, to enable an operator standing in front of the machine to observe the action on table 26, a mirror 210 is mounted on an extending bracket 212.

Pneumatic circuit

On the extending front of bracket 180 is mounted a plurality of control knobs 220, 222 and 224. These control the apparatus through the pneumatic circuit shown diagrammatically in FIG. 8.

More specifically, the pneumatic circuit 230 is supplied with compressed air from a suitable source 232 such as a compressor, through a check valve 234 to the system. It includes a manual three-way control valve 236, filter 238, pressure regulator 240, pressure gauge 242, buffer accumulator 244, lubricator 246 and muffler 247. The system also includes a pair of three-way, cycle starting, pilot valves 252 and 254 actuated by the knobs 222 and 224 just described, and a stop cycle valve 264 actuated by knob 220. Valves 252 and 254 are in series with a four-way cycle control valve 260. It also includes a shuttle valve 262 and a safety four-way pilot valve 266 operated by a solenoid 268 that is activated when grinding head motor 140 is operating.

The system is controlled partially in response to a cam mechanism 270 mounted on the carriage sub-assembly as shown in FIG. 4. It includes a first cam 272 which will shift a first three-way pilot valve 276. A second three-way pilot valve 280 can be actuated by a second cam 282 on device 270. These cams are shifted with movement of piston and shaft assembly of cylinder 160 (FIG. 3) that shifts the carriage. The rate of shifting of this cylinder can be controlled in both directions through a pair of speed control valves 290 and 292, each of which includes a check valve and a variable restricted orifice in conventional fashion. These lines to the opposite ends of this cylinder are connected to a four-way valve 296 which in turn is associated with a pair of sequence valves 298 and 300. These are operatively associated with cylinder 194 that actuates clamp 184, and are also associated with cylinder 116 that causes shifting of the finger elements for sole feeding and discharge. These in turn are associated with an air supply valve 302 to one line of which is associated a pressure regulator 304 and pressure gauge 306 and the other is connected to the shuttle valve 308.

Operation

The operator of the machine places a stack of soles in hopper assembly 14 so that the toes of the soles project upwardly and toward the front of the machine, with the back end of each sole in abutment with the lubricious back surface of panel 58. The hopper is kept constantly loaded. The bottommost sole is aligned with outlet open-

ing 60 (FIG. 5) of the hopper, and resting with its toe area on rollers 62, especially if a large sole.

When motor 140 for abrading cylinder 144 is operating, solenoid 268 operating four-way pilot valve 266 is active to put the valve in an operative position. The pneumatic circuitry (FIG. 8) is then ready to operate the machine once the cycle is started.

Assuming that a sole is already in the central work area of the table, under the clamp, and that the fingers are all elevated, and assuming that the feed-in fingers are immediately adjacent the sole that is beneath the clamp, just having fed it into position, and the discharge fingers are adjacent the discharge chute 24, knobs 222 and 224 are pushed by the operator. Pressure through valves 302 then actuate cylinders 116 and 194 to lower the feed fingers by retracting the piston of cylinder 116, and to close the clamp on the sole by extending cylinder 194 to pivot rocker arm 184. Then, sequence valve 300 opens to shift valve 296 to its first position. Pressure from valve 296 moves the carriage by actuation of cylinder 160 from right to left, to shift the revolving abrading cylinder 144 over the heel area of the clamped sole. This carriage also simultaneously shifts the lowered fingers so that the feed-in fingers are moved to a far position behind the bottom sole in hopper 14, and the discharge fingers are moved to a past-center position behind the sole which is just then abraded. When the carriage moves to the extreme left end, cam 282 actuates pilot valve 280 to shift valve 302 to its second position. Pressure ported through valve 302 then raises all of the feed fingers by extending cylinder 116. It also releases clamp 184 by retracting cylinder 194, after which sequence valve 298 opens to shift valve 296 to the second position.

Pressure from valve 296 then moves the carriage from left to right. This movement causes the elevated feed fingers to contact the bottom sole S (as illustrated in FIG. 10) in the stack, while the slanted beveled surfaces 71 and 73, which project above the sole, lift the overlying soles out of contact therewith. Thus, the lowermost sole is smoothly slid out of the hopper and toward the clamp in the center of the table. It is slid along the table while held aligned by flange 59. These feed fingers shift this sole directly beneath the clamp, and just over ledge 204 of the stop 200 as shown in FIG. 11. Simultaneously, the discharge fingers push the newly abraded and released sole from beneath the clamp and across the platform into chute 24. Simultaneously, the abrading cylinder is returned to its initial position as it follows the discharge fingers, to be able to make another pass on the next sole. At the end of the stroke, pilot valve 276 is actuated by cam 272 moving with the carriage to shift valve 302 back to its initial position.

The machining repeats these steps over and over until it is stopped by pressing knob 220 to actuate the cycle stop valve 264.

Certain additional advantages and certain additional unique features of the disclosed apparatus may be apparent to those in the art upon studying the foregoing specification and drawings which show the preferred form of the invention. It is conceivable that the particular details of structure could be modified slightly within the concepts presented without departing from the inventive concepts. Hence, the invention is to be limited only by the scope of the appended claims and the reasonably equivalent structures to those defined therein.

We claim:

1. A shoe sole abrading apparatus comprising: a sole supporting surface; sole clamping means shiftably cooperative with said surface to retain a sole thereon; sole abrading means; sole feed means movable toward said clamping means to feed a sole thereto, comprising a plurality of fingers shiftable from a first sole contacting feed position above said surface to a second return position below said surface; sole discharge means comprising a second plurality of spaced fingers shiftable from a first sole contact-

ing discharge position above said surface to a second return position below said surface; means to shift said first and second plurality of fingers; and shiftable carriage means mounting said sole abrading means, said sole feed fingers, and said sole discharge fingers to shift them simultaneously for first feeding a sole to the clamp, returning the abrading means, and discharging a sole, and then simultaneously returning the feed fingers, abrading the clamped sole, and returning the discharge fingers.

2. A shoe sole abrading apparatus comprising: an elongated platform, vertically slanted from front to back transverse to its elongated dimension; a shoe sole hopper at one end of said platform, and a discharge area at the other end thereof; a clamping device shiftable toward and away from said platform between said hopper and said discharge area; a sole retention means along said slanted platform at the lower edge thereof to guide a sole shifted to said clamp; a revolving sole abrading cylinder extending over a portion of said platform with its axis parallel thereto and movable along said platform in reciprocal fashion back and forth adjacent said clamping device to abrade the heel area of a sole clamped to said surface; and means to feed soles to said clamp from said hopper, and from said clamp to said discharge area.

3. A heel area shoe sole abrading device comprising: a sole support surface and sole clamping means adjacent thereto and cooperative therewith; a carriage movably mounted for reciprocation along said surface; a sole hopper spaced from said clamping means; a sole discharge area spaced from said clamping means opposite to said hopper; sole feed means mounted and positioned to reciprocate between said clamping means and said hopper; sole abrading means mounted and positioned to reciprocate back and forth past said clamp; sole discharge means mounted and positioned to reciprocate back and forth between said clamp and said discharge area; and all of said feed means, abrading means, and discharge means being operably mounted to said carriage to simultaneously move back and forth therewith.

4. A shoe sole abrading apparatus comprising: a slanted, flat sole feed table; a guide surface along the lower edge of said table; a clamp adjacent and above the central portion of said table; a power motor operably connected to shift said clamp toward said table; a sole stack hopper over one end of said table, having a pair of spaced side elements and a slanted back surface; said back surface having a slippery lubricious characteristic; the side element of said hopper closest said clamp having a sole outlet at its bottom, and having a resilient, shiftable spring finger biased to a position in front of said outlet, shiftable out of said outlet for egress of the bottom sole in said hopper; said table including an unloading station at the end of the table opposite said hopper; a carriage shiftable lengthwise along said table from said hopper, past said clamp, to said unloading station, and power means to shift said carriage; sole advancing fingers normally projecting above said table; power means operably connected to move said fingers below the table for recessed movement from said clamp back to said hopper to push the lowermost sole out of said hopper; a rotational abrading element mounted to said carriage to abrade a clamped sole, by moving past said clamp with said carriage simultaneously with return of said feed fingers to said hopper; push out, sole discharge fingers movable between said clamp and said discharge station and shiftable to a position projecting above said table to push abraded soles to said discharge station with advancement of said feed fingers and return of said abrading cylinder, and a position recessed below said table to return to said clamp with return of said feed fingers to said hopper and abrading movement of said cylinder.

5. The apparatus in claim 4 including a sole hook on said table at the upper portion thereof, adjacent said clamp, to catch the upper end of a sole fed to the clamp and prevent it from turning askew on said slanted table.

6. The apparatus in claim 4 wherein said hopper back

surface is at an obtuse angle to said table to limit contact of each stacked sole on said back surface to a line contact.

7. The apparatus in claim 4 wherein roller means is provided at the bottom of said hopper in said table, opposite said hopper back surface.

8. A heel area sole abrading machine comprising: a platform; abrading means adjacent said platform; a gravity feed sole hopper extending up from said platform; an outlet opening in the bottom of said hopper to allow the bottom sole to be pushed laterally therefrom, along said platform; spaced pushing elements mounted to shift laterally through the bottom of said hopper and having front faces to push the bottom sole out said outlet opening; said elements projecting above said surface to a height slightly greater than the thickness of a sole; and the upper portion of the pushing faces of said elements being sloped rearwardly to lift overlying soles off the pushed bottom sole.

9. A heel area sole abrading machine comprising: an operating platform having an elongated sole advance surface in one dimension; sole feed means at one end of said platform configurated to feed soles with their long dimension transverse to the elongated sole advance surface; sole discharge means at the opposite end of said platform; sole clamping and abrading means between said feed means and said discharge means; said platform being sloped thereacross at a substantial acute angle to cause the soles to slide toward the bottom thereof when moving along said platform; sole retention means along the lower portion of the platform; and means to push unabraded soles in upright position along said platform to said clamping and abrading means, and means to discharge the abraded soles.

10. A shoe sole abrading apparatus comprising: an elongated, planar sole feed table slanted across its short dimension; a guide surface along the lower end of said table; a clamp adjacent and above the central portion of said table; a power motor operably connected to shift said clamp toward said table to clamp a sole thereagainst; a sole stack hopper over one end of said table, having a pair of spaced side elements and a slanted back surface; the side element closest said clamp having a sole outlet at its bottom; said table including an unloading station at the end of the table opposite said hopper; a carriage shiftable lengthwise along said table from said hopper, past said clamp, to said unloading station, and power means to shift said carriage; a first plurality of spaced, sole feed advancing fingers normally projecting above said table; power means operably connected to move said fingers below the table for recessed movement from said clamp back behind said hopper; the finger furthest from said guide surface having a dogleg configuration parallel to the transverse slant of said table to accommodate soles of different length; the leading upper edge of said fingers being convexly curved to lift adjacent stacked soles while pushing the lowermost sole out of said hopper; a rotational abrading element mounted to said carriage to abrade a clamped sole, by moving past said clamp with said carriage simultaneously with return of said feed fingers to said hopper; push out, sole discharge fingers movable between said clamp and said discharge station and shiftable to a position projecting above said table to push abraded soles to said discharge station with advancement of said feed fingers and return of said abrading cylinder, and to a position recessed below said table to return to said clamp with return of said feed fingers to said hopper and abrading movement of said cylinder.

11. A shoe sole abrading apparatus comprising: a slanted, flat sole feed table having a guide surface along the lower edge thereof; a clamp adjacent and above the central portion of said table; a pivotal mount supporting said clamp, and a power motor operably connected to said mount to pivot it and shift said clamp toward said table; a sole stack hopper over one end of said table, having a pair of spaced side elements and a slanted back surface;

said back surface having a slippery lubricious characteristic, and being at an obtuse angle to said table to have a line contact only with soles stacked in said hopper; the side element closest said clamp having a sole outlet at its bottom, and having a resilient, shiftable spring finger in front of said outlet, shiftable out of said outlet for egress of the bottom sole in said hopper; roller means at the bottom of said hopper in said table, opposite said hopper back surface; said table including an unloading station at the end of the table opposite said hopper; a carriage shiftable lengthwise along said table from said hopper, past said clamp, to said unloading station, and power means to shift said carriage; a first pair of spaced, sole feed advancing fingers normally projecting above said table; shiftable arms mounting said fingers and supported by said carriage; said arms and fingers being movable with said carriage between said hopper and said clamp; power means operably connected to said arms to move said fingers below the table for recessed movement from said clamp back to said hopper; the leading upper edge of said fingers being convexly curved to lift adjacent stacked soles while pushing the lowermost sole out of said hopper; a sole hook on said table at the upper portion thereof, adjacent said clamp, to catch the upper end of a sole fed to the clamp and prevent it from turning on said slanted table; a rotational abrading

cylinder mounted to said carriage to abrade a clamped sole, by moving past said clamp with said carriage and simultaneously with return of said feed fingers to said hopper; a pair of push out, sole discharge fingers movable between said clamp and said discharge station; pivotal arms mounting said discharge fingers to said carriage and shiftable to move said fingers to a position projecting above said table to push abraded soles to said discharge station with advancement of said feed fingers and return of said abrading cylinder, and a position recessed below said table to return to said clamp with return of said feed fingers to said hopper and abrading movement of said cylinder.
